HARD ROCK DRILL HEAD

Orlando Arthur Letts, Montreal, Quebec, Canada

Application May 6, 1948, Serial No. 25,387

7 Claims. (Cl. 255—64)

1
This invention relates to improvements in a hard rock drill head, appertaining particularly to one having replaceable teeth or nibs of exceptionally hard and durable material.

Among the objects of the present invention are to provide a drill head of simpler, stronger and better design in which the super-hard teeth can be easily and quickly secured; interlocking teeth held in a novel manner and so formed and fitted to the head as to distribute and dissipate impact with the minimum of injury to the teeth and head and without danger of relative accidental displacement of the parts; and a secure and positive yet easily releasable connection between the head and drill rod shank.

A further object of the invention is to provide a new rock drill especially designed for the extra hard rock encountered in the pre-Cambrian shield that may be manufactured at a reasonable price yet is capable of cutting drill costs from 50 to 80 percent.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a sectional elevation of my assembled drill head;

Figure 2 is an elevation of the stripped or skeleton head;

Figure 3 is a top plan and Figure 4 a bottom plan thereof;

Figure 5 is an elevation of the end of the drill steel or shank;

Figure 6 is a section therethrough as taken on line 6—6, looking in the direction indicated by the arrows;

Figures 7, 8 and 9 are a side elevation, outside end elevation and bottom plan respectively of the instant form of tooth;

Figure 10 is an elevation of the centre locking sleeve; and

Figures 11 and 12 are elevations of the teeth and shank locking rings respectively.

My improved drill calls for a head 1 of novel and unique design having a shank or drill rod socket 2 in its base 3 and radial slots 4 in its

slightly flared outer end 5 preferably in the form of diametrical or diagonal slots intersecting at the head's axis and dividing the same into sector-shaped quarters. The base 6 of the slots 4 slope downwards toward the centre of the head through which runs the usual cleaning fluid axial bore 8. Concentric with this bore where it emerges in the intersecting grooves there is a shallow annular seat 9, of greater diameter than the width of the slots 4. At the inner corners formed by the intersecting slots 4 an angular or L-shaped seat 10 is cut, extending down in rectangular form for about a third of the depth of the slots.

A circumferential groove 11 is cut in the outer rim of the flaring end 5 extending from a level about the middle of the depth of the slots to about three-quarters of their depth. It is for the accommodating of a spring keeper or locking ring 12. A somewhat similar encircling groove 13 is cut in the skirted lower end 3 and likewise accommodates a locking ring 14.

Seating in the shallow seat 9 is an axially positioned hollow post or sleeve 15 that serves in a sense as an anvil, rising three-quarters of the way to the top of the head and includes a pair of well spaced, externally projecting annular flanges 16.

The teeth or nibs 17 standing vertically and disposed radially are of a width to fit tightly in the slots 4. Both top and bottom 18 and 19 are sloped or tapered to the outside of the head, the latter at an incline to conform with the slope of the base 6 of the accommodating slot 4. The top 18 is bevelled equally on each side to provide a central cutting ridge 20 and rises, as seen in Figure 1, substantially above the quartered and fluted outer end of the head 5. Furthermore, these teeth 17 extend radially beyond the circumference of the slightly flared bit head 1, their outer ends 21 below the end of the head then tapering in to meet and conform to the contour of the bit thus allowing a sufficient body in the projecting top and ends of the teeth to withstand considerable wear and still maintain the gauge or size of the drill hole for the life of the teeth.

About two-thirds of the way in from its bevelled and sloping top 18, the outer end 21 of each tooth, where it registers with the bit head encircling groove 11, is correspondingly notched as at 22 for the reception of the locking ring 12. The inner, centre post engaging ends 23 of the teeth are concaved to conform to the circular form of the sleeve 15 and have a registering pair of spaced transverse notches 24 in which the centre post flanges 16 are accommodated to prevent the relative longitudinal displacement of tooth and

post. The inner corners of the teeth where they engage the adjoining teeth on either side are mitered as at 25 and, near the top 18 reaching from about the upper notch 24 to the bottom of the bevel to the cutting ridge, they have lateral wings 26 flush with the miters 25 on contacting faces and of otherwise rectangular form for seating in and conforming to the shape of the confronting portion of the L-shaped seat 10 in each case. These wings provide an increased engaging area for joining teeth to receive inwardly directed impact besides holding the teeth against radial separation from the head.

The drill rod shank 27 for releasable reception in the socket 2, that preferably has a slight taper towards its inner end, is formed with three eccentric or cam-like surfaces 28 for locking engagement with corresponding eccentric surfaces 29 on the interior of the socket 2 for jamb locking engagement on the relative rotation of the parts. Additionally the skirt 3, under the groove 13 has three circumferentially elongated radial slots 30 through into the socket and in the shank 27, in registry with these slots are circular radially disposed bores 31 to receive separable locking pins or dowels 32 kept in place by the spring locking ring 14. It will thus be seen that while the cam locking structure of the shank and bit will provide a tight coupling of the parts, these dowel pins held in place by the spring ring will eliminate any possible accidental separation of shank and bit.

From the foregoing description taken in connection with the accompanying drawings, it will be manifest that a hard rock drill head is provided that will fulfill all the necessary requirements of such a device, but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described the invention, what I claim as new and desire to secure by Letters Patent is:

1. A rock drill head having radial slots in the outer end thereof, the inner ends of said slots being widened and the base of said slots sloping downwards toward the centre of said head, replaceable teeth receivable in said slots having lateral wings on their inner ends fitting in the widened inner ends of said slots and having sloping bottoms corresponding with the slope of the base of said slots and oppositely sloping upper edges; and means releasably securing said teeth in said head against longitudinal displacement.

2. A rock drill having intersecting diagonal slots quartering the outer end thereof, the base of said slots sloping downwards toward the centre of said head, a centre post insertable in said head at the intersection of said slots, radially disposed teeth in said slots with their bottoms sloping to correspond with the bases of said slots and their upper edges oppositely sloping so that they taper outwardly at both top and bottom, said teeth all engaging said centre post at their inner ends interlocking means on said centre post and the inner ends of said teeth, and a drill-encircling teeth-securing means.

3. A rock drill head having intersecting slots quartering the outer end thereof, the base of said

slots sloping downwards toward the centre of said head, replaceable teeth receivable in said slots with exposed cutting edges on their exposed tops declining from the centre outwards and their bottoms sloping inwards to correspond with the bases of said slots so that both top and bottom edges of said teeth taper outwardly and the hammering action of the drill tends to force said teeth toward the centre of said head, a removable centre post in said head at the intersection of said slots engaged by and serving as an anvil for the inner ends of said teeth, interlocking means on said centre post and said teeth preventing relative longitudinal displacement, and releasable means securing said teeth in said head.

4. A rock drill head having intersecting diagonal slots quartering the outer end thereof, the base of said slots sloping downwards toward the centre of the head, replaceable teeth receivable in said slots with top exposed cutting edges declining from the centre outwards and their bottoms sloping inwards to correspond with the bases of said slots so that both top and bottom of said teeth taper outwardly and the hammering action of the drill tends to force said teeth toward the centre of said head, a centre post in said head engaged by the inner ends of said teeth, said centre post and teeth having inter-engaging longitudinal anti-displacement connection, and releasable means securing said teeth in said head.

5. A cylindrical rock drill head having intersecting diagonal slots quartering the outer end thereof, the base of said slots sloping downwards toward the centre of said head and a well formed at the base of said slots at their intersection, replaceable teeth receivable in said slots with exposed cutting edges on their exposed tops declining from the centre outwards, spaced vertical ends paralleling the axis of said head and their bottoms sloping inwards to correspond with the bases of said slots so that the hammering action of the drill tends to force said teeth toward the centre of said head, a centre post coaxial in said drill head serving as an anvil for the inner ends of said teeth and formed as an externally flanged sleeve seating in a well in the bottom of the intersecting slots, the inner ends of said teeth having notches to accommodate the centre post flanges, said head having a circumferential groove substantially above the bottom of the diagonal slots therein, said teeth having correspondingly positioned notches across their outer ends and a releasable spring keeper ring in said groove and notches.

6. A rock drill head having intersecting diagonal slots quartering the outer end thereof, the base of said slots sloping downwards towards the centre of said head, and L-shaped seats at the corners formed by said intersecting slots, replaceable teeth receivable in said slots with exposed cutting edges on their exposed tops declining from the centre outwards and their bottoms sloping inwards to correspond with the bases of said slots so that both top and bottom of said teeth taper outwardly and the hammering action of the drill tends to force said teeth toward the centre of said head and wings extending laterally from opposite sides of said teeth at their inner edges for accommodation in said seats, a centre post in said head engaged by the inner ends of said teeth, interlocking means on said post and the inner ends of said teeth for preventing relative longitudinal displacement and means securing said teeth in said slotted head and lying flush with the contour of said head.

7. A rock drill head having intersecting slots quartering the outer end thereof, an annular groove in said head above the bottom of said slots, a socket in the base of said head having eccentric, cam-like surfaces, a groove about the socket skirt of said head, slots through from the base of said second groove into said socket, removable teeth in said intersecting slots with notches in their outer ends registering with said first mentioned groove, a central anvil-like sleeve engaged by the inner ends of said teeth and held against longitudinal displacement thereby, a spring ring seating in said first mentioned groove and the notches in the outer ends of said teeth, a drill rock shank fitting in said socket having correspondingly formed eccentric, cam-like surfaces and radial bores extending therein in registry with the slots cut through into said socket, dowel pins through said registry slots and bores and a spring keeper ring in said second groove 20 confining said dowel pins.
